PROCESS AND APPARATUS FOR PRODUC-
ING INDICIA TUBES FOR DISPLAY DE-
VICESAlfonse Kaufman, Long Beach, N. Y., assignor to
Biolite Incorporated, New York, N. Y., a cor-
poration of New York

Application June 2, 1936, Serial No. 83,100

4 Claims. (Cl. 226—116)

In accordance with the present invention, there is provided a rapid method of producing display devices of the type wherein the effectiveness of the device is produced by a moving column of liquid confined in a transparent form which may constitute a letter, or other indicia, or a portion thereof, either alone or as a portion of a word, name, slogan, or the like, and wherein attention of an observer is attracted by the moving liquid within the form, the motion being produced by bubbles rising rapidly through the liquid in its transparent container.

More particularly, the present invention relates to glass tubing containing a colored liquid preferably of low boiling point and maintained under sub-atmospheric pressure and wherein the liquid is broken up into separated sections by bubbles generated in the liquid solely by application of heat to the tubing, the motion of the bubbles in the tubing being an important means of attracting attention to the display.

The source of heat for producing the bubbles also conveniently supplies an illumination for the display, which adds materially to the attractiveness of the motion imparted by the bubbles in the liquid.

In carrying out the present invention, a glass tube is provided of sufficiently small diameter to maintain a meniscus of liquid and to preserve moving columns of liquid and gas (vapor) produced from the liquid; and the present invention is concerned principally with the method of making the tube and introducing the liquid therein.

Generally speaking, the structure of the present invention is a glass tube of the above-indicated character, in which a volatile liquid such as acetone, ether, alcohol, or other volatile liquids containing dissolved coloring matter has been introduced, the tube being highly evacuated so as to substantially depress the already low boiling point of the liquid, whereby upon application of only moderate warmth to the tube, a portion of the liquid becomes vaporized, and the resulting vapors form bubbles which pass through the liquid, causing displacement and movement thereof, the vapors recondensing to liquid as soon as they reach the cooler portions of the tube; and the present invention relates to the shaping, evacuation and filling of the tubes with the liquid, whereby the desired display will be produced.

One of the objects of the invention, therefore, is to provide an improved process for the production of displays of the above-indicated character, wherein the steps are simple and are in-

terrelated sequentially to produce a highly expeditiously executed process from the initial manipulations effected on the tube to the completed indicia.

A further object of the invention is to provide an improved process for evacuating and filling the tube with liquid.

A still further object of the invention is to provide a tube of the character above-indicated, which is preformed into a desired indicia, and which is provided with a simple means for enabling the tube to be evacuated, filled with a predetermined amount of liquid, and sealed.

A further object of the invention is to provide improved means for expeditiously carrying out the operations of evacuating the preformed tube and to fill the tube with a measured quantity of fluid wherein the operations of evacuating, filling and sealing of the tube may be carried out by simple manipulations of the said means and without necessitating handling or manipulation of the tube itself during these operations.

Further objects and advantages of the present invention will become apparent as the description proceeds, and the features of novelty will be pointed out in particularity in the appended claims; and the invention accordingly comprises the sequence of steps of the operation, the features of construction, combination of elements, and arrangement of parts which will be exemplified in the construction hereinafter set forth and the scope of the application of which will be indicated in the claims.

The invention will be understood more readily by reference to the accompanying drawings in which

Fig. 1 is a fragmentary elevational view of a glass tube showing the first stage of production of a desired indicia.

Fig. 2 is a similar view showing a further stage of production of the indicia.

Fig. 3 is a view similar to Figs. 1 and 2, but taken at right angles to Fig. 2 and showing the application of a sealing tube to Figs. 1 and 2.

Fig. 4 is an elevation of a tube bent into the form of a simple letter or indicia, showing the tube ready for the attachment of the tube of Figs. 1, 2 and 3.

Fig. 5 is a view of the indicia tube of Fig. 4 showing the tube of Figs. 1, 2 and 3 applied thereto and the exhaust neck sealed off to form the completed tube with liquid therein.

Fig. 6 is a sectional elevation of an apparatus for evacuating and filling a tube with fluid, the

- tube having been prepared in accordance with the showings of Figs. 1 to 5 inclusive.
- Fig. 7 is a sectional elevation of the apparatus shown in elevation at the left of Fig. 6, showing 5 the tube in exhausting and filling position.
- Fig. 8 is a sectional elevation of one of the valves of the apparatus of Fig. 7, the view being taken generally on the line 8—8 of Fig. 7 and showing the valve in open position.
- 10 Fig. 9 is a view similar to Fig. 8, but showing the valve in closed position.
- Fig. 10 is an enlarged view of the valve construction shown at the left of Fig. 7, showing the valve in open position.
- 15 Fig. 11 is a sectional elevation of a modified form of apparatus of the type shown in Fig. 10.
- The present invention is directed to the method of producing the character or letter indicia for a display device which is adapted to be mounted 20 in a casing and which has an exposed translucent or transparent part in which a liquid may be seen to bubble. As has been indicated above, the indicia forming the display device are formed of evacuated tubes partially filled with a low boiling 25 liquid, the pressure in the tubes being sufficiently low so that only a very moderate amount of heat needs to be applied to the tubes to produce a rapid formation of bubbles in the liquid as vaporization takes place in the sub-atmospheric 30 pressure in the tubes. Heat is supplied to give the energy required to produce the bubbling and light may be supplied to illuminate the liquid and the bubbles. The translucent part is in the form of a character such as a letter, numeral, a sign, 35 an emblem or a design, or any combination thereof. It will be understood, also, that the term "translucent" as employed in the description and claims herein is intended to embrace the term "transparent".
- 40 The liquid occupies but part of the space within the device, the pressure within the remainder of the space being at less than atmospheric at room temperature. A volatile liquid such as acetone or ether is preferably employed. This may have 45 sufficient natural color for display purposes, or coloring matter may be added. The bubbling is attained by heating the lower end of the device (indicia tubes) whereby, as will be apparent as the description proceeds, a part of the liquid 50 is vaporized and passes through the remainder of the liquid to the top of the device when the normal room temperature causes the vapors to condense and fall back as a liquid toward the bottom of the device. The result is, therefore, 55 that when the indicia are formed, filled with liquid as will be described herein, and assembled properly to produce the desired display, they will have moving gaseous and liquid elements therein for enhancing the display effects of the device, the 60 gaseous phase of the components of the device being produced solely by the application of heat to the indicia, as described above, which produces an intermittent but regular motion within the liquid.
- 65 The liquid in the indicia tubes may be colored in any convenient way as by having a dye in solution as a constituent. Colored suspensions or powders may be used. The liquid remains in contact with the heated portion of the tube for a 70 relatively short period during the operation of the device, and the liquid which is so in contact changes constantly so as to retain its color after long use, neither dye nor suspended coloring matter baking out on the walls of the heated portions of the tube.

The accompanying drawings illustrate the manipulative operations involved in the production of the completed indicia, and there are also shown in the drawings details of the apparatus, in preferred form, which is used for exhausting 5 the tubes and for filling the tubes with liquid while maintaining the said tubes and liquid therein under subatmospheric pressures, and for holding the tubes for enabling them to be readily sealed off for retaining the liquid under vacuum 10 in the completed tubes, all of which is accomplished without necessitating handling or manipulation of the tubes during the evacuating, filling and sealing off of the tubes.

Referring more particularly to the drawings, it 15 will be seen that A represents generally a glass tube which is sealed at one end and which has been blown, adjacent to its sealed end, into an enlarged bulb 18 by any well known glass manipulating practice, this bulb 18 forming finally a 20 fluid reservoir, as will become apparent. The tube A is also provided, immediately adjacent to the bulb 18, with a constricted portion 20, which is formed into the soft glass by any standard 25 practice. Conveniently this is done by holding the glass tube in a jaw-clamping apparatus, while heating the portion of the tube thus held and the sealed end thereof until the glass becomes plastic, the open end of the tube being attached to a convenient source of air pressure, whereby the enlargement of the bulb 18 is produced.

Following these operations the tube is again heated at the constricted portion 20 until it becomes plastic, when it is bent sharply as indicated at 22 in Fig. 2, the air pressure being still 35 applied, forming a capillary passage.

The tube A is then heated at a localized spot above the bend 22, as indicated at 24, with application of air pressure until a hole is blown through the tube at the point 24, which provides 40 an orifice to which is sealed a branch tube 26, care being taken to assure the tube 26 being secured to the tube A in a perfect seal all around the orifice 24. The side tube 26 is intended to serve as an exhaust tube as will be apparent hereinafter.

At this stage of the proceedings, a second glass tube B may be taken, and sealed at one end, as indicated at 28. The tube is then heated in a region 30 and bent in a predetermined manner 50 such as is indicated for example in Fig. 4, wherein the bend is made at right angles, thereby producing the letter L. Care is taken during the bending to apply air pressure, as is well known in glass bending, so as to maintain the tube in the region of the bend, of substantially the same diameter as the remainder of the tube. The tube B may then be heated at the elbow of the bend while applying air pressure thereto, until an opening 32 is blown through the tube. This opening 60 32 serves as the point of attachment of the tube A, this tube being sealed to the tube B at the opening 32, so as to provide a perfect seal all around the opening. The other end 34 of the tube B is sealed off, so that the tube B is open to 65 the air only through the tube A and the side tube 26.

The tube B is now to be evacuated and filled with the desired quantity of liquid.

In order to do this, the apparatus shown in 70 Figs. 6 to 11 inclusive conveniently is employed, since it permits the evacuation and filling of the tube without requiring any handling or manipulation of the tube during the evacuating and filling operations.

In order to carry out these operations, the tube is mounted in an improved evacuating and filling apparatus indicated generally at C in Fig. 6, and which will be described in greater detail hereinafter.

This apparatus is connected by a delivery tube 36 to a distillation flask or similar receptacle 38 which contains a supply of volatile liquid 40, which liquid may be acetone, or ether or other suitable volatile liquid, which is heated in a constant temperature water bath 42, of any desired standard type.

The flask 38 is provided with a usual reflux condenser 44, through which water is maintained in circulation, this condenser being fitted into the flask 38 through a hole in a two hole stopper 46, the delivery tube 36 passing through the other hole of the stopper, and down into the flask 38 to approximately the bottom of the flask.

As will be pointed out in greater detail hereinafter, the apparatus C is attached to a vacuum line through a connection such as is indicated by tube 48, whereby upon suitable manipulation of a valve system, which will be described hereinafter, liquid from the flask 38 will be drawn over through the tube 36 until a gage tube 50, forming a part of the apparatus C becomes filled with the liquid, this gage tube being the measure of the liquid which is to be inserted in the indicia tube B.

The liquid 40 in the flask 38 is heated by the bath 42 to its boiling point so that there will be no dissolved air or other gases present in the liquid that is drawn over through the tube 36.

The bath 42 is conveniently a constant temperature water bath, it being provided with a cover 52 through which passes an electric heater 54, this heater being immersed in a body of water 56 contained in the water bath receptacle 42.

The temperature of the bath may be controlled by any suitable thermostatic control mechanism in circuit with the heater 54, such mechanism being operable responsive to temperature changes in the water 56 of predetermined amounts, a rise of temperature above that for which the thermostat control is operative shutting off the supply of current to the heater 54, so that the temperature of the bath will fall for a predetermined amount, when the temperature responsive mechanism will again become operative to restore the current flow through the heater 54.

A type of temperature responsive means is indicated at 58 on the drawings. A lining of heat insulating material, such as rock wool, may be provided around the interior of the water bath receptacle 42, such a lining being indicated at 60.

Referring now to Fig. 7, it will be seen that the apparatus C comprises a housing 62 in which is mounted a plug 64 which is exteriorly threaded as shown at 66, and which is provided with an interior duct 68. This duct 68 is branched as indicated at 70, this branch leading to a vacuum line, not shown, through a rubber connection 72, which is controlled by a valve 74.

The plug 64 is provided with a recess in its threaded end, this recess containing a resilient washer 76 and clamping mechanism 78, this mechanism including retractable clamping devices which are operable by means of a handle 80 and a yoke or the like 82 which is connected with a cap 84 fitting over the threaded end of the plug 64.

The resilient washer 76 and the cap 84 have

aligned passages therethrough, which passages are also aligned with the duct 68.

The clamping device 78 is also apertured with the opening therethrough being in alignment with the passages in the cap 84 and the washer 76.

There is thus provided a means whereby the branch tube 26 of the indicia may be brought into connection with the duct 68, and held in position during the evacuating and filling operations by a simple movement of the lever handle 10 80, so as to bring the clamping members 78 into clamping engagement with the tube 26. The indicia tube B thereby is held in exhausting and filling positions.

Within the housing 62 there is provided also a 15 plug 86, which is threaded exteriorly at 88, and which contains a duct 90 which has a branch tube 92 leading therefrom. The duct 90 is connected to the duct 68 in the plug 64 by means of a rubber connector 94, which is controlled by a valve 96. 20

Registering with the duct 90 is a gage tube 98 which is mounted in a resilient rubber washer or the like 100, which is held in a cap 102 threaded on the exterior threads 88 of the plug 86.

The branch 92 of the duct 90 is connected, as 25 by means of a rubber connector 104 to the liquid delivery tube 36, the rubber connector 104 being controlled by a valve 106.

This entire apparatus is mounted on a stand 108 which is suitably secured, as by screws or the like 110, to a work table 112, attachment to the support 108 being made conveniently by means of a flange 114 on the housing 62, the mounting being made by means of suitable screws or the like 116 which pass through the flange 114 and 35 bracket 156 secured by a screw or the like 157 to the support 108. The bracket 156 is provided with an opening 159 through which the plug 66 of the apparatus C extends.

Before the indicia tube B is mounted in operative position with respect to the apparatus C, a small amount of the volatile liquid is introduced into the tube, conveniently by means of a dropper which introduces the liquid into the tube B through the tube 26.

The tube 26 then is inserted in the clamp 78, and is secured in place by suitable manipulation of the handle 80. The valve 106 is closed, so that there will be no flow of liquid from the flask 38 through the tube 36, and the valves 96 and 74 are 50 opened so that the indicia tube B and the gage tube 98 will be brought into connection with the suction line not shown through the branch tube 70 and the rubber connector 72.

The system is thus exhausted, and the liquid 55 previously inserted in the tube B is vaporized, thereby driving out all the air which is present in the system.

While the suction is still being applied to the tube B, the valve 96 is closed and the valve 106 60 is opened thereby bringing the gage tube 98 into communication with the liquid delivery tube 36, so that liquid will flow from the flask 38 through the delivery tube 36, branch tube 92, duct 90 and into gage tube 98. The gage tube 98 is of 65 such capacity that when it is emptied, the proper amount of liquid will be introduced into the indicia tube B.

In order to drain this tube 98, the valves 106 and 74 are closed and the valve 96 is opened, 70 thereby enabling the liquid from the gage tube 98 to flow through the duct 68, the tube 26 and into the tube B, filling the tube B with the requisite measured amount of liquid.

The tube 26 is then sealed off by means of a 75

flame applied to the tube at approximately the point 118, whereby the liquid in the tube B is maintained under vacuum, the tube B having been exhausted as has been described above.

5 The handle 80 is then operated to release the remaining portion of the tube 26 which is discarded and the indicia tube B is then ready to be mounted in the assembled display device.

10 The finished tube is illustrated in Fig. 5 from which view it will be seen that the tube A may be provided with a coating of black paint 120 at the region of the bend, for facilitating heat absorption to accentuate the vaporization of the liquid in the desired manner.

15 Figs. 8, 9, and 10 show details of the construction of the valves employed in the apparatus C, these valves being of a generally similar type in each instance.

20 Fig. 8 illustrates the construction of the valve 106, the view showing the valve in open position so that liquid is free to flow through the rubber connector 104. It will be seen that the valve comprises simply a compression member 122 which is mounted in slots 124 and 126 in a frame 25 comprising the side members 128 and 130 and an end member 132, the tube 104 being inserted between the end member 132 and the compression valve member 122, whereby upon actuation of the latter, the tube 104 becomes compressed and closed, as indicated in Fig. 9.

25 Actuation of the compression valve member 122 is accomplished by means of a rotatable actuator 134 which is mounted on a shaft 136 which in turn passes through the side members 128 and 30 35 130 of the valve frame, the shaft 136 being held in place by suitable means such as cotter pins 138. The actuator 134 is eccentrically mounted relatively to the shaft 136, so that it acts as a cam for operating the compression valve member 122. The actuator 134 is manipulated by 40 means of a handle 140.

35 Fig. 8 shows the compression member 122 positioned in its guide members 128 and 130 so as to allow the tube 104 to be open for admission 45 of the liquid, whereas Fig. 9 shows the handle 140 turned into closing position so as to cause the actuator 134 to move the compression valve member 122 in its slotted guides 128 and 130 so as to squeeze the tube 104 closed, the parts illustrated in Fig. 9 therefore showing the valve in closed position.

40 The valve 96 is illustrated as being a construction entirely similar to that of valve 106, so that the description of Figs. 8 and 9 will apply also 50 to the construction of the valve 96.

45 As illustrated further, the valve 74 is also of a generally similar construction, in that this comprises a movable compression member 142 which is mounted in guides 144 and 146, and which is actuated by a rotary actuator 148, which is eccentrically mounted, as indicated at 150, movement of the actuator 148 being accomplished by manipulation of a handle member 152.

55 Control of the suction through the tube 72 is effected by opening and closing this tube by corresponding movements of the actuator 148 and the compression valve member 142, the tube being retained between the compression valve member 142 and a retaining member 154, which is shown as being bolted or otherwise secured to the flange 114 of the filling apparatus and to the top 156 of the work table, the securing of the retaining member 154 being accomplished by means of screws 158 which pass through the flange 160 of the retaining member 154 and the

flange 114 of the filling apparatus and the top 156 of the work table.

60 It will be seen therefore that the necessary controls for the suction and for the admission of the filling liquid into the indicia tube B are very simple in construction and in operation, and that when the indicia tube B is placed in filling position, it is securely clamped therein by the clamping action of the clamp 78 onto the filling tube 26.

65 When the tube has been filled with liquid to the desired amount, as indicated by the drainage of the gage tube 98, the filling tube 26 is sealed off as has been mentioned above, there being left merely a short stub 162 which is of an immaterial length.

70 In the form of apparatus illustrated in Fig. 11, the construction is somewhat similar to that described above, except for the fact that the plug 64 is replaced by the modified plug 64a, which is provided with an interior duct 164 which is 75 80 85 90 95 100 105 110 115 120 125 130 135 140 145 150 155 160 165 170 175 180 185 190 195 200 205 210 215 220 225 230 235 240 245 250 255 260 265 270 ditions and uses. It is also to be understood that the following claims are intended to cover all of the generic and specific features of the invention herein described, and all statements of the 5 scope of the invention which, as a matter of language, might be said to fall therebetween.

What is claimed is:

1. The method of producing display devices, which comprises introducing a small quantity of 10 relatively volatile liquid into a preformed indicia tube, releasably clamping the said tube in an evacuating and filling apparatus including a measuring device for containing a suitable supply of liquid for introduction into the tube, simultaneously evacuating the tube and measuring device by applying suction thereto, interrupting the suction while maintaining the tube and device evacuated, introducing liquid into the device 15 from a suitable supply thereof, and draining the liquid into the evacuated indicia tube.
2. In the production of display devices, the combination of means for evacuating a preformed indicia tube and for filling the tube with a display liquid, the said means comprising a housing, 20 branched tubular passages in the housing, the branch from one of the passages being adapted to be connected to a supply of the said liquid, the branch from the other passage being adapted to be connected to a source of suction, a closable 25 connection between the passages, a gage device communicating with the first-mentioned passage for measuring the liquid from the said supply, valve means in the housing adapted to close and to open the connection between the passages, a 30 valve mechanism for controlling admission of liquid from the supply to the gage tube, valve means for controlling suction through the second-mentioned passage, and releasably operated clamping instrumentalities for securing the 35 indicia tube in position relative to the housing and in communication with the source of suction and with the gage tube whereby, upon proper manipulation of the valves, the indicia tube and gage tube may be evacuated, the suction cut off while 40 the tubes are maintained evacuated, the gage tube filled with the liquid, the supply of liquid cut off and the liquid drained from the gage tube into the indicia tube to fill the latter with measured 45 quantity of liquid all while obviating any handling or manipulation of the indicia tube.
3. In the production of display devices, in combination, a housing including means for releasably clamping a pre-formed indicia tube in evacuating and filling position, devices for evacuating the tube, instrumentalities for introducing a measured quantity of liquid into the tube while 50 the said tube is evacuated, and means for intro- 55

ducing an initial small amount of liquid into the indicia tube while suction is applied thereto for displacing all air from the indicia tube prior to filling thereof with liquid; and valves operable in predetermined sequence for controlling the said devices, instrumentalities and means while obviating manipulation of the indicia tube.

4. In the production of display devices, the combination of means for evacuating a preformed indicia tube and for filling the tube with a display liquid, the said means comprising a housing, a branched tubular conduit in the housing, the branch from the said conduit being adapted to be connected to a main supply of the said liquid, the remaining portion of the said conduit being 10 adapted to communicate with a source of suction, connecting means comprising a plug member removably mounted in the housing and including a longitudinally extending tubular conduit having a plurality of branches leading therefrom, a connection for the plug interconnecting the said tubular conduit therein with the said conduit in the housing which is adapted to communicate with the source of suction, a connection joining one of the said branches in the plug to the source of suction, a second connection for connecting another branch in the plug to an auxiliary supply of liquid; a collar mounted upon the plug, clamping instrumentalities within the said plug, an opening extending through the 15 collar and clamping instrumentalities in alignment with the longitudinal conduit through the plug for receiving and for releasably securing the indicia tube in exhausting and filling position, a gauge tube mounted on the housing in registry 20 with the said conduit in the housing, valve means in the housing adapted to close and to open the connection between the plug and housing, a valve mechanism for controlling admission of liquid from the main supply to the gauge tube, a suction-controlling valve in the suction line leading 25 from the housing to the source of suction, and suction-controlling means intermediate the plug and auxiliary supply of liquid whereby, upon proper manipulation of the valve, the indicia 30 tube and gauge tube may be evacuated while liquid is introduced into the indicia tube from the auxiliary liquid supply and evacuated to expel air from the indicia tube, the suction then cut off while the gauge tube and indicia tube are maintained evacuated, the gauge tube filled with liquid 35 from the main source, the supply of liquid cut off, and the liquid drained from the gauge tube into the indicia tube to fill the latter with a measured quantity of liquid, all while obviating any handling or manipulation of the indicia tube.

ALFONSE KAUFMAN.
